DESIGN FOR A CAN PERFORATOR AND DISPENSER

Redvers Darrell Silvera, Los Angeles, Calif.

Application June 2, 1934, Serial No. 52,022

Term of patent 14 years

To all whom it may concern:

Be it known that I, REDVERS DARRELL SILVERA, a citizen of the United States, and a resident of Los Angeles, in the county of Los Angeles and State of California, have invented a new, original, and ornamental Design for Can Perforator and Dispenser, of which the following is a specification, reference being had to the accompanying drawing, forming a part thereof:

Figure 1 is a plan view of my can perforator and dispenser.

Figure 2 is a plan view of the same with the closure member swung into open position.

Figure 3 is a bottom plan view of my perforator and dispenser with the closure member swung into open position.

Figure 4 is a side elevation.

Figure 5 is an end view.

I claim:

The ornamental design for a can perforator and dispenser, as shown.
